Philip Sawyer Lier Kennedy

UNITED STATES PATENT OFFICE.

CHARLES F. KERRIGAN, OF BROOKLYN, NEW YORK.

CLOSURE FOR COLLAPSIBLE TUBES.

1,282,591.

Specification of Letters Patent.

Patented Oct. 22, 1918.

Application filed April 15, 1916. Serial No. 91,283.

To all whom it may concern:

Be it known that I, CHARLES F. KERRIGAN, a citizen of the United States, residing at Brooklyn, county of Kings, and State of New York, have invented certain new and useful Improvements in Closures for Collapsible Tubes, fully described and represented in the following specification and the accompanying drawings, forming a part of the same.

This invention relates to certain improvements in containers or tubes of pliable metal, such as are used for holding tooth paste, shaving cream and the like, and commonly known as collapsible tubes.

It is one of the objects of the invention to provide a distributing device for such containers, including a distributing nozzle and cap which will be permanently secured thereto, so that it cannot be readily removed therefrom and lost.

It is a further object of the invention to provide such a distributing device which shall be of such construction as to permit the container to be effectually closed when not in use, and thus prevent the entrance of foreign matter to the container. It is a further object of the invention to provide a construction which will reduce to a minimum the grinding of the parts on opening and closing of the container, thus preventing bits of metal from getting into the container, which may cause discoloration of the contents thereof.

With these and other objects in view, the invention consists in certain novel parts and constructions which can best be understood from a detailed description of the same, and such description will now be given in connection with the accompanying drawings, in which—

Figure 1 is a side view of a flexible metal tube with the improved distributing device shown in section in closed position;

Fig. 2 is a similar view showing the parts in open or distributing position, part of the tube being broken away; and

Fig. 3 is a section taken on line 3—3 of Fig. 2.

Referring now to these drawings, the container marked 1 is of the well-known type now employed for holding tooth paste, shaving cream and the like, made of pliable metal, commonly known in the art as a

collapsible tube, the contents being removed from the container by compressing it.

In accordance with the invention, the container or tube is provided with a distributing nozzle having a distributing opening and with a closing cap coöperating with the nozzle to close the opening so as to effectually prevent the entrance of foreign matter to the tube. The distributing opening is, furthermore, preferably formed so that the contents of the container will not be smeared on the cap and prevent a complete closing of the opening. While the nozzle might be formed separately from the container and be suitably secured thereto, in the preferred construction, and as illustrated, the tube is formed with an integral nozzle in which is located the distributing opening. In the preferred construction, as that shown in Figs. 1 and 2, the top of the container is stamped or otherwise shaped to form a projection 3 which projects inwardly a short distance into the container and is for a purpose hereinafter referred to, formed with an interiorly threaded aperture or opening 4, closed at the bottom, as shown. Around this projection 3 near its top is formed, by suitably striking up the metal, a recess 5, the outer walls of which are of less diameter than the body of the tube and form a flange 6, the upper end of which is flat, as indicated at 7, to provide a seat for the cap. The distributing opening leads from this recess 5 and may be of various configurations. Preferably, there will be but one opening, as indicated at 8, and preferably, furthermore, this opening is formed in a plane diagonal to the vertical plane of the tube. The purpose of this construction is that, when the paste is ejected from the tube, it will be forced out at an angle to the nozzle and cap, and gumming of the cap will be prevented. Furthermore, in the best constructions, and as shown, this opening will extend from the upper portion of the recess 5 at the junction between the top edge of the flange 6 and seat 7, so that the entrance to the container of bits of metal, which might be ground off during the opening and closing movement of the cap, is to a large extent prevented.

Coöperating with the nozzle of the container 1 is a closing top or cap. This cap may vary somewhat in construction, but, as illustrated, is preferably in the form shown

in Figs. 1 and 2. As there shown, the cap is formed with a flat top and is provided with a milled edge 9 to provide a convenient gripping surface for operating it. The cap has an interiorly depending stem 10, having its lower portion threaded, as at 11. This cap works in the threaded opening 4 in the nozzle; before referred to, this opening being of sufficient depth to receive the stem. 5

10 This cap-piece is formed, as shown, around the stem 10 with a depending flange or skirt 12, which is dimensioned so that when the cap is in closed position, this flange extends below the distributing opening 8 and co- 15 operates with the flange 6 before referred to, and effectually closes the opening. In the best construction, a sealing disk of suitable material, as a thin disk of cork 14, is provided in the interior of the cap for more 20 effectually closing the opening.

To effect one of the main objects of the invention, a construction is provided whereby the cap when once forced into position cannot be readily removed from the tube 25 and loss or misplacement of the cap is prevented. This construction may, of course, be considerably varied. In the construction illustrated in Figs. 1 and 2, which is a convenient one, the inner edge of the seat 7 30 which is marked 7' is left with a slight flange of metal which, after the threaded end of the cap has been screwed into the opening 4, is turned in over and forms a stop against which the threads 11 on the 35 end 10 of the cap will be stopped, and thus effectually preventing the cap from being accidentally removed from the tube.

While the invention has been shown and described in what is thought to be its best 40 and most convenient form, it will be understood that variations may be made in the specific form and arrangement of the nozzle

and cap, and that such variations are within the scope of the invention and claims hereunto appended.

What is claimed is:

1. A container for tooth paste and the like, composed of pliable metal and provided with a distributing nozzle having a flat top forming a seat, a distributing opening below the seat and extending angularly to the vertical plane of the nozzle so as to distribute material sidewise therefrom, a closing cap having threaded engagement with the nozzle and a part movable to a position below the distributing opening to entirely close the same and seating on the flat top of the nozzle when in closed position, and means for preventing the cap from being entirely unscrewed from the nozzle. 50

2. A tube for tooth paste and the like, composed of pliable metal and provided with a distributing nozzle formed integral therewith having a flat top forming a seat, said nozzle being formed with an inwardly projecting interiorly threaded portion, a distributing opening at the side of the nozzle extending angularly thereto so as to distribute material sidewise from the nozzle and a closing cap having a stem in threaded engagement with said threaded portion, and a skirt closing the distributing opening in the nozzle, said cap being prevented from being entirely unscrewed from the nozzle by bending in the metal of the nozzle seat to 70 form a stop above the threads of the cap stem.

In testimony whereof, I have hereunto set my hand, in the presence of two subscribing witnesses.

CHARLES F. KERRIGAN.
